Henrik J. Schmidt

UNITED STATES PATENT OFFICE

CLARENCE LA GRANGE, OF HOWARD BEACH, NEW YORK

COOLING SYSTEM PUMP FOR OUTBOARD MOTORS

Application filed May 16, 1930. Serial No. 452,940.

The invention relates to pumps and has for its object to provide an efficient pump for circulating water through the cooling system of the engine on so-called outboard motors. Another object is to provide a pump of simple construction, occupying only a small space, with all its parts readily accessible, and which can be manufactured at a comparatively low cost.

10 These and other objects and advantages will be readily understood from the following description and from the accompanying drawings of a preferred embodiment in which, however, certain modifications might 15 be made without departing from the scope of the invention. In the drawings

Fig. 1 is a side elevation of certain parts of an outboard motor, drawn partly in section and showing the pump;

20 Fig. 2 is a front elevation of Fig. 1, taken on line 2—2 of that view;

Fig. 3 is a cross-sectional view taken on line 3—3, Fig. 1; and

25 Fig. 4 is a cross-sectional view taken on line 4—4, Fig. 1, and drawn to a larger scale than the other views.

Referring now to all the views, the housing of the under-water parts of an outboard motor is indicated by the numeral 10. The 30 propeller shaft 11, to which the propeller 12 is secured, rotates in the housing and is driven in the regular manner by the vertical main shaft 13. The means employed for imparting motion from the main shaft to 35 the propeller shaft are not shown as they do not form part of the invention.

A circular recess 14 is formed in the housing and a water inlet passage 15 is cast integral with the housing and leads 40 from the front of the housing to the recess. A cover 16 is bolted over the recess and is provided with an inwardly extending bearing 17. The rear wall 18 is likewise provided with a bearing 19 which also extends into 45 the recess. A short shaft 20 rotates in these bearings and rotation is imparted to it from the main shaft 13 by a pair of bevel gears 21 and 22.

A paddle wheel, consisting of a hub 23 50 and a plurality of arms 24 to which paddles

25 are secured, is mounted on the shaft 20 and rotates with this. The water as it enters the recess 14 through the passage 15 is, by the action of the paddle wheel, forced upward through an outlet 26. This outlet 55 communicates with a passage 27 cast in the main shaft casing 28 and from this passage the water is suitably piped to the jacket of the engine.

Having described my invention, what I 60 claim as new and wish to protect by Letters Patent is:

In combination with an outboard motor having a submerged housing and a vertical shaft rotating therein, a circular recess 65 formed in one side of said housing, a cover for said recess, water inlet and outlet passages leading to and from said recess, a paddle wheel rotating in said recess on an axis at right angle to that of the vertical shaft 70 in the housing, and means for transferring rotary motion from said vertical shaft to the paddle wheel.

CLARENCE LA GRANGE.
